(57) **CLAIM**

The ornamental design for a digital television with graphical user interface, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a digital television with graphical user interface; and,

FIG. 2 is a front view thereof.

The broken line drawing of the digital television forms no part of the claimed design. The broken lines shown in the drawings represent portions of the graphical user interface that form no part of the claimed design. The broken lines shown in the drawings illustrating state and/or country borders form no part of the claimed design.

1 Claim, 2 Drawing Sheets
(2 of 2 Drawing Sheet(s) Filed in Color)

FIG. 2
